US00D440300S

(12) **United States Design Patent**
Högberg et al.

(10) Patent No.: **US D440,300 S**
(45) Date of Patent: ** Apr. 10, 2001

(54) **RING BAG FOR THE CENTRIFUGATION OF BLOOD COMPONENTS**

3,987,961 * 10/1976 Sinn et al. 494/45
5,114,396 * 5/1992 Unger et al. 494/45
5,723,050 * 3/1998 Unger et al. 210/782

(75) Inventors: **Niclas Högberg; Emanuel Hälgren, both of Karlskoga; Peter Pihlstedt, Stockholm, all of (SE)**

* cited by examiner

(73) Assignee: **Sanguistech AB, Karlskoga (SE)**

Primary Examiner—Marcus A. Jackson

Assistant Examiner—Reid Hecker

(74) Attorney, Agent, or Firm—Pearne & Gordon LLP

(**) Term: **14 Years**

(57) **CLAIM**

The ornamental design for a ring bag for the centrifugation of blood components, as shown and described.

DESCRIPTION

Nov. 19, 1999 (SE) 99-2083

FIG. 1 is a top plan view of our new design, the bottom plan view being a mirror image thereof;

(51) LOC (7) Cl. **24-01**

(52) U.S. Cl. **D24/107**

(58) **Field of Search** D24/107, 118, D24/216, 219, 232; 210/360.1, 781, 782, 787; 422/72, 101; 494/34, 45; 604/410

FIG. 2 is a top and side perspective view of our new design; and,

FIG. 3 is a front elevational view of our new design.
